UNITED STATES PATENT OFFICE.

HARRY M. MANNHEIMER, OF ST. LOUIS, MISSOURI.

FOUNTAIN-PEN.

SPECIFICATION forming part of Letters Patent No. 769,554, dated September 6, 1904.

Application filed May 16, 1904. Serial No. 208,235. (No model.)

To all whom it may concern:

Be it known that I, HARRY M. MANNHEIMER, a citizen of the United States, and a resident of St. Louis, Missouri, have invented certain new and useful Improvements in Fountain-Pens, of which the following is a specification containing a full, clear, and exact description, reference being had to the accompanying drawings, forming a part hereof.

10 My invention relates to fountain-pens; and it consists of the novel features herein shown, described, and claimed.

In the drawings, Figure 1 is a perspective of a fountain-pen embodying the principles of my invention. Fig. 2 is a longitudinal sectional detail upon an enlarged scale. Fig. 3 is a plan of the ink-feeder, parts being broken away. Fig. 4 is a cross-section on the line 4-4 of Fig. 2. Fig. 5 is a cross-section on the line 5-5 of Fig. 2. Fig. 6 is a cross-section on the line 6-6 of Fig. 2.

Referring to the drawings in detail, the ink-receptacle 7 is tubular in form, so as to serve as the main frame of the penholder, there being a removable cap 8 at its upper end and a packing 9 within the cap to make a tight joint. The lower end of the ink-receptacle is reduced in size, and there is an enlarged screw-threaded portion 10 near the center of the receptacle. The extreme lower end of the receptacle is adapted to serve as an ink-feeder, there being a small opening 11 connecting the chamber 12 with the ink-feeder groove 13. A shell 14 is loosely mounted upon the lower end of the ink-receptacle, the upper end 15 of the shell being tapered and exteriorly screw-threaded, and a ferrule or coupling 16 is adjustably mounted upon the screw-threaded portion 10, with the upper end of the shell 14 screw-seated in the lower end of the coupling, so that the shell 14 may be adjusted up and down on the ink-receptacle. The pen-clamp 17 is mounted in the lower end of the shell 14, and the pen 18 is inserted 45 into the lower end of the shell outside of the clamp 17 in position to cover the ink-feeding

groove 13, the point of said groove terminating slightly below the upper end of the feeding-slot 19 of the pen.

Any ordinary writing-pen may be used with 50 my fountain-penholder. The pen is inserted into the shell 14, then the shell is placed in position to bring the pen into proper relation with the ink-feeding mechanism, then the shell 14 is held securely in position relative 55 to the ink-receptacle, and the coupling 16 is adjusted to hold the shell 14 in that position. The coupling 16 should fit comparatively tight upon the screw-threads 10 and may be secured down upon the shell 14 until it tightens 60 up by virtue of the tapered thread 15. Then the parts are secured together and may be used until it is desired to change pens.

One of the principal objects of my invention is to produce a fountain-pen in which ordinary steel pens may be used.

If desired, the screw-threads 15 may be omitted, in which case the taper should be retained, so that the shell may be pressed tightly into the coupling.

The leading features of my invention are an ink-receptacle forming the frame of the penholder, a pen-holding mechanism adjustably mounted upon the ink-receptacle, so as to provide means of using pens of different sizes, 75 and feeding mechanism leading from the ink-receptacle to the pens.

I claim—

1. In a fountain-pen: an ink-receptacle forming the main frame of the penholder; a 80 coupling screw-seated upon the ink-receptacle; and a pen-holding device adapted to be attached to the coupling; substantially as specified.

2. In a fountain-pen: an ink-receptacle 85 forming the main frame of the penholder; a coupling screw-seated upon the ink-receptacle for adjustment up and down; and a pen-holding device adapted to be attached to the coupling; substantially as specified.

3. In a fountain-pen: an ink-receptacle; a coupling adjustably mounted upon the ink-

receptacle; and a pen-holding device adapted to be attached to the coupling; substantially as specified.

4. In a fountain-pen: an ink-receptacle; a pen-holding device slidably mounted upon the ink-receptacle; and means of fastening the pen-holding device to the ink-receptacle; substantially as specified.

In testimony whereof I have signed my name to this specification in presence of two subscribing witnesses.

HARRY M. MANNHEIMER.

Witnesses:

F. C. CRISLER,
JOHN C. HIGDON.
